UNITED STATES PATENT OFFICE

157,362

VANITY CABINET OR THE LIKE

Mary A. Francis, Highland Park, Mich.

Application August 9, 1948, Serial No. 148,010

Term of patent 7 years

(Cl. D33—19)

To all whom it may concern:

Be it known that I, Mary A. Francis, a citizen of the United States and a resident of Highland Park, Wayne County, Michigan, have invented a new, original, and ornamental Design for a Vanity Cabinet or the like, of which the following is a specification, reference being had to the accompanying drawing, forming part thereof.

In the drawing:

Fig. 1 is a view in perspective of a vanity cabinet embodying the invention, showing the same with the doors closed;

Fig. 2 is similar view, but showing one of the doors open;

Fig. 3 is a plan view of the cabinet, showing both doors open.

I claim:

The ornamental design for a vanity cabinet or the like, as shown.

MARY A. FRANCIS.
